United States Patent Office

Des. 191,725
Patented Nov. 7, 1961

191,725

SEWING MACHINE OR SIMILAR ARTICLE

Sidney J. Hamlett, Parma, Ohio, assignor to White Sewing Machine Corporation, Cleveland, Ohio, a corporation of Delaware

Filed Oct. 3, 1960, Ser. No. 62,347

Term of patent 14 years

(Cl. D70—1)

Fig. 1

Fig. 2

Fig. 4

Fig. 5

Fig. 3

Fig. 6

Fig. 7

FIG. 1 is a top plan view of the sewing machine;
FIG. 2 is a front elevational view thereof;
FIG. 3 is a rear elevational view thereof;
FIG. 4 is an end elevational view as seen from the left of FIG. 2;
FIG. 5 is an end elevational view as seen from the right of FIG. 2;
FIG. 6 is a front quarter perspective view of the sewing machine; and
FIG. 7 is an enlarged fragmentary perspective view as seen partially from below of the lamp housing on the sewing machine.

I claim:
The ornamental design for a sewing machine or similar article, as shown.
